FURNACE CONSTRUCTION

John E. Anderson, Chicago, Ill., assignor to
Plibrico Jointless Firebrick Company, Chicago,
Ill., a Corporation of Illinois

Application July 28, 1930. Serial No. 471,165

11 Claims. (Cl. 72—101)

This invention relates to furnace constructions and more particularly to means for anchoring a lining to a furnace wall.

This anchoring means is intended to be used in connection with a refractory lining applied to furnaces, such lining being initially formed of a plastic material. While the anchoring means is intended particularly for this use, it can, of course, be used for many other purposes, as will be readily understood. In applying a refractory lining to furnaces in plastic condition, it is necessary to provide anchoring means for securing the lining, as it is formed, to the furnace wall. It is also necessary that the anchoring means be flexible to the extent that it will allow relative movement of the lining under conditions of use, both horizontally and vertically and independently of the retaining wall, so as to avoid subjecting the lining and the wall to undesirable stresses and resulting injury.

In the copending application of Ivon S. Pieters, Serial No. 123,825, filed July 21, 1926, for Flexible anchors, there is disclosed an anchor for use with a furnace of brick setting and which meets the above requirements. I now find it desirable to apply such an anchor to a furnace having a steel or sheet metal casing and also to furnaces of hollow wall construction, that is, furnaces wherein the refractory lining or inner wall is spaced away from the outer or retaining wall and which serves to insulate, to a certain extent, the refractory lining of the furnace chamber from the outer retaining wall.

It is one of the features of my invention that the anchor can be secured directly to the casing by bolting or welding it thereto. This is a decided advantage in a furnace of hollow wall construction inasmuch as the anchor can be secured directly to the backing of the refractory material, which is of some heat resisting material, instead of having to pass therethrough and be connected to the outer retaining wall.

Another important feature of the invention is the provision of means for fastening such anchors to a furnace of hollow wall construction and of such form as will limit the movement of the refractory wall toward and away from the retaining wall and thus eliminate the use of headers for such a purpose.

Other objects and advantages of the invention will be apparent from the following detailed description when taken in connection with the accompanying drawings in which:

Figure 1 is a top plan view of the anchor of

my invention as used with a furnace of hollow wall construction;

Figure 2 is a fragmentary sectional view of the anchor taken along the line 2—2 of Figure 1;

Figure 3 is an elevational view of the anchor as used with a steel casing wall;

Figure 4 is a vertical sectional view through a furnace wall and lining, of hollow construction, showing the application of the invention to such a construction; and

Figure 5 is a section taken substantially along the line 5—5 of Figure 4.

Referring more in detail to the drawings: As best seen in Figure 4, I have shown my invention as applied to a furnace of hollow wall construction. The outer or retaining wall of the furnace setting comprises an outer casing 1 of steel or sheet metal against the inner side of which abuts a wall 2 of heat resisting material, such as asbestos or magnesium. A suitable backing 3, formed of refractory material in sheet form, defines the outer face of an inner wall or refractory lining 4, which is disposed in spaced relation to the inner face of wall 2, leaving an air space 5 between the two walls. The wall 4 is formed of refractory material which, when applied, is in a stiff plastic condition, this material being applied in lumps or chunks which are beaten together by a suitable mallet to form a monolithic structure, and the backing 3 provides a retaining form or support against which the wall is formed.

The flexible anchor assembly for anchoring the lining wall 4 to the retaining wall 1 is designated in its entirety by the reference numeral 6 and comprises three members 7, 8 and 9. The member 8 comprises a single strip of strap metal bent intermediate its end into the shape of a reverse or ogee curve to form two arms 10 and 11, the purpose of which will be hereinafter explained. Anchor part 7 comprises a base 12 having a relatively long upturned arm 13 and a relatively short upturned arm 14. A slot 15, (Figures 1 and 2) of sufficient width to accommodate easily the arm 10 of member 8, is formed in base 12 adjacent arm 10 as by stamping out a lig 16 from the base. Further details of this anchor member may be found in the above mentioned copending application. In applying the member 7 to member 8, it is simply slipped over the arm 10 which extends upwardly through the slot 15. Due to the slot 15 being of greater width than the arm 10, as illustrated in Figure 1, the anchors will permit independent expansion and contraction of the inner wall 4

in all directions in the plane thereof due to the relative vertical and transverse movement between the arm 10 and the member 7.

The anchors are fastened to the retaining wall 5 or casing 1 by means of anchor part 9 which comprises a rod of circular cross section. The rod 9 is threaded for a small portion of its length at either end for the reception of nuts 17 and 18, and near one of its ends is bowed to 10 form a portion 19 of substantially U-shaped configuration. It will be noted that the bowing of rod 9 forms in effect two flanges 20 and 21, of which flange 20 is adapted to extend through 15 the backing 3 for the reception of member 8 which is secured thereon by means of the nut 17. It will also be noted that when the member 8 is mounted upon said rod, the arm 11 of member 8 abuts the backing 3 and that the reverse or 20 ogee curvature of said member is sufficient to allow the anchor part 7 to play freely both horizontally and vertically on arm 10 without binding. The U-shaped portion 19 of the rod 9 abuts against the outer side of backing 3 and the 25 inner side of the wall 2, with the flange 21 thereof extending through said wall and the outer casing 1, and a channel frame member 30, to which it is secured by the nut 18. By reason of the U-shaped portion of the rod abutting against the wall 2 and the backing 3, the walls 30 are thus held in spaced relation to preserve the air space 5 and the use of headers, which are usually used for such a purpose, is thus eliminated.

In Figures 1 and 2, I have shown a modification 35 in the manner of mounting the anchors upon the wall. In cases of hollow wall construction where it is not desired to use the member 9 for securing the anchor to the retaining wall, the anchors may be secured directly to the backing 40 3 and by means of a nut and bolt 22 and 23 respectively, which passes through the backing 3 and the arm 11 of member 8. In such a construction it will, of course, be necessary to provide some means for spacing the backing 3 from 45 the retaining wall or wall of insulation 2, all as is well understood in the art. The construction of the members 7 and 8 is the same as that referred to in Figure 4 and a further description of them is not deemed necessary.

In Figure 3, I have shown the anchor as applied to a furnace having a metal casing 1a and a wall of insulation 2a. The member 8a, which has the same function as the member 8, is of substantially Z-shaped configuration. The arm 55 11a, of member 8a, is secured to the casing 1a in any suitable manner, such as by welding or bolting it thereto. The reverse or ogee curvature of such member is sufficient to extend through the wall of insulation 2a so that the anchor member 7 may be mounted upon the arm 10a for free translatory movement in both a horizontal and a vertical direction.

In practice a number of lining anchors comprising the member 8 are employed, being spaced a suitable distance apart and fastened to the outer casing of the furnace or to the backing or support of the monolithic material, as the case may be. The wall 4 is then built up to the member 8. The member 7 is then connected to the member 8 and the plastic material then pounded around said anchor. Any suitable means may be provided to prevent the plastic material from entering slot 15 and interfering with the operation of the anchor after the wall has become set and vitrified. Such a means is disclosed, for ex-

ample, in the copending application of Roger F. Wiley, Serial No. 475,147, filed August 14, 1930, for Lining anchoring means. It is, however, to be understood that any other suitable means, such as the placing of moistened paper or asbestos about the point between the anchor members, may be employed. The important object is to assure that the connection between the lining anchoring member and the wall anchor member is such that the lining is free to expand and contract both vertically and horizontally after it has become set and vitrified, and independently of the retaining wall. The wall 4 is separated into sections by means of the Corbel construction 32, Figure 4, which is supported by 80 means of angle strips 33 and 34 bolted or otherwise suitably secured to frame member 30. Such a construction serves to transmit the weight of the lining to the channel members 30 and thus prevents the weight of the lining itself from causing buckling and resultant breaking away and spalling of the wall. The refractory lining 4 is disposed below the boiler tubes 31, where the heat is most intense. The upper lining 4a may be of fire brick or other suitable refractory material, as the heat is not as intense above the tubes 31, as below these tubes. After the wall 4 has been erected in the manner described, it is suitably dried and vitrified and the furnace is 90 then in condition for use.

What I claim is:

1. In a furnace construction, an outer retaining wall, an inner wall disposed in spaced relation to said outer wall comprising a lining of refractory material and a backing therefor, anchor members embedded in said lining, and means securing said members to said backing and said outer wall.

2. In a furnace construction, an outer retaining wall, an inner wall comprising a lining of refractory material and a backing therefor, anchor members for securing said lining to said backing, and means for securing said anchor members to said backing and for holding said inner wall in spaced relation to said outer wall.

3. In a furnace construction, an outer retaining wall, an inner wall including a lining of refractory material, spacing members extending from the outer wall and disposed in abutting relation to said inner and outer walls for holding said inner wall in spaced relation to said outer wall, and means mounted upon the inner portion of said spacing members for accommodating expansion and contraction of said inner wall in every direction in the plane thereof independently of the outer wall.

4. In a furnace construction, an outer retaining wall, an inner wall including a lining of refractory material, means for holding said inner wall in spaced relation to said outer wall and against movement away therefrom, and means mounted upon the inner end of said last named means and disposed entirely within the plane of said inner wall for accommodating expansion and contraction of said inner wall in every direction in the plane thereof independently of the outer wall.

5. In a furnace construction, an outer retaining wall, an inner wall disposed in spaced relation to said outer wall and comprising a lining of refractory material and a backing therefor, and means anchoring said lining to said backing, said means accommodating expansion and contraction said lining in every direc-

tion in the plane thereof independently of the backing and said outer wall.

6. In a furnace construction, an outer retaining wall, an inner wall disposed in spaced relation to said outer wall and comprising a lining of refractory material and a backing therefor, and a flexible anchor connecting said lining directly to said backing, said anchor permitting said lining to expand and contract in every direction in the plane thereof independently of said support and said outer wall.

7. In a furnace construction, an outer retaining wall, an inner wall disposed in spaced relation to said outer wall and comprising a lining of refractory material and a backing therefor, anchor members embedded in the lining wall, and anchor members secured to said backing and having universal connection with the lining wall anchor members, whereby the lining wall is free to expand and contract in every direction in the plane thereof independently of said support and said outer wall.

8. In a furnace construction, an outer retaining wall, an inner wall disposed in spaced relation to said outer wall and comprising a lining of refractory material and a backing therefor, anchor members embedded in the lining wall, anchor members secured to said backing, and tongue and slot connections between the anchor members permitting expansion and contraction of the inner wall in every direction in the plane thereof independently of said backing and said outer wall.

9. In a furnace construction, an outer retaining wall, an inner wall comprising a backing and a refractory lining, an anchor member secured to said lining, an anchor member on the backing and having universal connection to the

lining anchor member, and means securing the anchor member on the backing to said backing, said means acting to hold the inner wall spaced away from the outer wall and also securing the inner wall and the outer wall together.

10. In a furnace construction, an outer retaining wall, an inner wall disposed in spaced relation to said outer wall and comprising a lining of refractory material and a backing therefor, an abutment member extending from the outer wall and having a U-shaped portion disposed in abutting relation to said outer wall and said backing for holding said backing spaced from said outer wall, and means carried by said abutment member for securing said lining to said backing and for holding said lining against movement away from said backing, said means accommodating expansion and contraction of the lining in every direction in the plane thereof independently of the backing and said outer wall.

11. In a furnace construction, an outer retaining wall, an inner wall disposed in spaced relation to said outer wall and comprising a lining of refractory material and a backing therefor, spacing members extending from the outer wall and disposed in abutting relation to said outer wall and said backing for holding said backing spaced from said outer wall, and means carried by said spacing members for securing said lining to said backing and for holding said lining against movement away from said backing, said means accommodating expansion and contraction of the lining in every direction in the plane thereof independently of the backing and said outer wall.
